UNITED STATES PATENT OFFICE.

WILLIAM L. LOVELAND, OF MILWAUKEE, WISCONSIN, ASSIGNOR TO ALLIS-CHALMERS COMPANY, OF MILWAUKEE, WISCONSIN, A CORPORATION OF NEW JERSEY.

ROASTING-FURNACE.

No. 919,197.

Specification of Letters Patent.

Patented April 20, 1909.

Application filed January 17, 1906. Serial No. 296,447.

To all whom it may concern:

Be it known that I, WILLIAM L. LOVELAND, a citizen of the United States, residing at Milwaukee, in the county of Milwaukee and State of Wisconsin, have invented certain new and useful Improvements in Roasting-Furnaces, of which the following is a specification.

This invention relates to temperature control of a shaft.

This invention has utility when applied to ore roasting furnaces and comprises a simple and effective means for maintaining a sufficiently low temperature in the arms that the arms are not weakened by the heat.

Referring to the drawing, the hollow rotatable shaft 1 has a single compartment or passage extending longitudinally thereof. The shaft 1 has also a plurality of lateral openings communicating with tapered hollow radiating arms 2. Concentric with the shaft 1 and extending longitudinally thereof in its compartment is the pipe 3. In the event that water is used as the temperature controlling medium, it may be introduced from pipe 4 into the pipe 3, conveyed to near one end of the shaft 1, and from thence pass into the compartment of the shaft 1 and freely circulate into the arms and along the compartment to the outlet pipe 5. The hollow rotatable shaft 1 having arms 2, serves to water jacket the inlet pipe 3. A second valve controlled outlet 6 for the compartment of the shaft 1, is shown at the opposite end of the compartment from the outlet pipe 5.

It is customary to support the stirring arms and shaft in the type of apparatus disclosed by this specification upon a step bearing, and as the shaft and arms especially when full of water are of considerable weight, a great deal of heat is developed at the step bearing.

As shown by the drawings, the shaft is

cast in sections, a separate section being provided for the step bearing, the lower part of this section being recessed at 7 to receive the bearing pin. The upper part of this member is also recessed, as at 8, the two recesses approaching each other closely but leaving a sufficient thickness of metal at 9 to support the weight of the shaft and arms, even when full of water.

The pipe 3 through which the cooling water is admitted to the interior of the shaft is extended well down within the recess 8 of the lowermost section of the shaft, and the water discharging downwardly through said pipe will first abstract the heat in this lower section which has resulted from the friction of the shaft upon the bearing.

The upper recess of the shaft section which forms the stop bearing is narrowed in its lower portion so as to provide for a narrow channel at the outlet pipe 3 and surrounding same and this narrow channel is at the lowest point of the chamber within the hollow shaft. The effect of such construction is to entirely obviate any clogging at this point and all sediment tending to form will be speedily washed away and the channel kept open for efficient circulation.

What is claimed and it is desired to secure by Letters Patent is:

A hollow sectional shaft, arms on the shaft, one of said sections forming a step bearing and being recessed and said recess being narrowed in its lower portion, and means for supplying water to said shaft and for discharging same within the narrow portion of said recess.

In testimony whereof I affix my signature in presence of two witnesses.

WILLIAM L. LOVELAND.
